UNITED STATES PATENT OFFICE.

JOHN D. MURPHY, OF CHICAGO, ILLINOIS.

TUBE-FLANGING MACHINE.

SPECIFICATION forming part of Letters Patent No. 486,984, dated November 29, 1892.

Application filed February 15, 1892. Serial No. 421,608. (No model.)

To all whom it may concern:

Be it known that I, JOHN D. MURPHY, a citizen of the United States, residing at Chicago, in the county of Cook and State of Illinois, have invented a new and useful Improvement in Tube-Flanging Machines, of which the following is a specification.

My invention relates to improvements in machines for flanging the ends of tubes generally, though my object is more especially to provide an improved machine or implement for use in boiler-making to upset the ends of the tubes against the tube-sheets.

My object is, further, to provide, in combination with the upsetting mechanism, means for shaping the flange into a bead, improved means for securing the implement in a tube, and still further to provide a machine or implement for the purposes described which shall be particularly quick and effective in its operation, readily adjustable into operative position, strong, durable, and comparatively inexpensive to manufacture.

In the drawings, Figure 1 is a broken sectional view of the end portion of a boiler, showing tubes partly in section and partly in elevation and illustrating my improved device in longitudinal section and secured in operative position; Fig. 2, an enlarged view in elevation of the rotary upsetter and beader; Fig. 3, a view in elevation of a bar or frame forming part of the construction shown in Fig. 1; Figs. 4 and 5, views in elevation, respectively, of an expanding sleeve or mandrel and a tubular wedge or expander forming part of the improved mechanism for securing the device in operative position; Fig. 6, a longitudinal section of the expanding sleeve or mandrel, the section being taken on line 6 of Fig. 7; Fig. 7, a section taken on line 7 of Fig. 6 and viewed in the direction of the arrow, and Fig. 8 a broken sectional view illustrating a simplified construction of my improved device applied to a boiler-tube.

A is a tube-sheet, and B boiler-tubes. Before my device is brought into use for upsetting and beading the ends of the tubes the tubes are cut to proper lengths, inserted at their ends through the openings in the tube-sheets, and a shoulder *t* formed upon each tube at the inner or water side of the tube-sheet by means of a suitable tube-expander.

C is securing means for fastening my improved device in operative position. It comprises a sleeve *s*, formed, preferably, in four longitudinal segments held together by expansible rings *r* of springy metal. The rings fit in circumferential sockets *r'* near opposite ends of the sleeve. Through the center of the sleeve is an opening *s'* of flaring shape, the enlarged end being at one end of the sleeve and the reduced end terminating in a straight opening or passage *s''*. Between the ends of the reduced part *s''* of the opening through the sleeve is a recess *s'''*, adapted to receive an internally-threaded nut *s⁴*, which is held secure against turning. Extending through the sleeve is a rod *q* of a diameter which permits it to pass freely through the openings *s''* and provided at one end with a thread *q'* to engage the thread of the nut *s⁴*. The opposite end of the rod is squared, as shown at *q²*, and adjacent to its squared end the rod is threaded, as shown at *q³*. Surrounding the rod *q* is a tubular wedge or conical expansion-core *p*, adapted to enter the flaring opening in the sleeve *s*. At the large end of the tubular wedge *p* is a washer *o*, which is held against longitudinal movement upon the rod *q* by a pin *o'*. On the outer surface of the sleeve *s*, near its outer flared end, is a circumferential bead or shoulder *s⁵*. In their normal state the segments of the sleeve are contracted by the springs *r*, so as to reduce the diameter of the sleeve 85 and permit it to be readily inserted in a tube B. The sleeve is inserted into a tube B until its shoulder *s⁵* registers with the inner circumferential socket of the tube formed under the bead *t*. The rod *q* is turned from its 90 squared end *q²* to travel through the nut *s⁴*, and causes the washer or collar *o'* to bear against the end of the tubular wedge *p*. The wedge *p* is thus forced into the sleeve *s*, and by bearing against the sides of the flaring passage *s'* expands the sleeve against the inner surface of the tube B and causes the shoulder *s⁵* to enter and engage the bead-socket *t*. When the sleeve is thus expanded, it and the rod *q* are held rigidly in place.

D is a frame having an elongated slot *n* to receive the rod *q*, a threaded opening *n'* for a set-screw *m*, a threaded opening *n''* to receive the threaded end portion of a shaft *l*,

and an opening n^8 , affording a bearing for a shaft k . The set-screw m is provided with a swiveled base-block m' , adapted to fit upon the end of a tube, as shown, and at its opposite end the set-screw is squared, as shown at m^2 . The outer end of the shaft l is squared, as shown at l' , and near its inner end it is provided with a shoulder l^2 . Extending from the shoulder l^2 is a threaded reduced portion 10 or stem l^3 of the shaft l , carrying a ring l^4 . The ring l^4 is held against a ferrule l^5 , interposed between it and the shoulder l^2 by a nut l^6 . The ring l^4 fits closely but loosely into a tube B and affords a bearing for the shaft l . Turning upon the shaft l is a head or circular block i , provided around its periphery at one side with cogs i' . In the face of the block i is a deep circular recess i^2 . Crossing the recess i^2 are radially-extending 15 shafts i^3 , located equidistant from each other and carrying wheels h , which revolve in the recess i^2 . The peripheries of the wheels h are concave, as shown, and alternate wheels—that is, every second wheel of the series—are formed on their outer sides with circumferential cutting-edges h' . Upon the shaft l at the side of the block i is a loose washer l^7 and at the side thereof adjacent to the yoke D is a loose washer l^8 . Confined between the washers l^7 l^8 is a spring l^9 , which operates normally 20 to press the rotary block i in the direction away from the yoke against the shoulder l^2 on the shaft l . On the shaft k is a pinion k' , which meshes with the cogs i' on the block i . 25 At its outer end the shaft k is provided with a crank k^2 .

In the construction of boilers the tubes B are equidistant apart, so that each tube is surrounded by a series of tubes located at a uniform 30 distance radially from it. The frame D is so arranged that it may be adjusted at its slot n upon the rod q , so that the upsetting-wheels h may engage one of the tubes nearest to that in which the rod q is secured or a tube farther away. To adjust the device in 35 position, the frame D is passed at its socket n over the rod q and a clamping-nut q^4 , placed upon the threaded end q^3 of the rod. The set-screw m and the nut q^4 are then turned to 40 clamp the yoke firmly in position to press the upsetting-wheels against the tube to be operated upon and to contract the spring l^9 . Turning 45 of the crank k^2 produces rotation of the pinion k' and block i , causing the wheels h to travel around the end of the tube. Pressure 50 of the spring l^9 thus exerted against the ends of the tube causes the latter to be upset by the concave wheels h . The force of the spring l^9 may be augmented from time to time by 55 tightening the nut q^4 . As the end of the tube is upset the cutting-edges h' on the wheels h shave off metal at the outer circumferential edge of the flange produced by upsetting the end of the tube and form the bead x shown. In the construction shown in Fig. 8 the rotary block carrying the upsetting-wheels is mounted directly

upon the rod q , which also thus performs the function of the shaft l of the device shown in Fig. 1. This machine is of a more simple construction than that described; but it necessitates adjusting the securing means in a tube each time the device is to be operated. The crank k^2 is fastened directly upon the block i and the frame D , shaft k , and set-screw m are dispensed with. In the use of this simpler construction, as the securing means C is placed in each tube, the separate tube-expander referred to above for forming the shoulder t may be dispensed with, and the shoulders t produced by the expansion of the bead s^5 on the sleeve s . The construction shown in Fig. 1 is preferred because I find it takes less time to produce the shoulder t with an expander in common use than to remove and replace the securing means C each time the upsetting mechanism is to be operated.

While I have shown my improved device in the form I prefer to employ, it may be modified in the matter of details of the construction without departing from the spirit of my invention as defined by the claims.

What I claim as new, and desire to secure by Letters Patent, is—

1. In a device for upsetting the ends of tubes, the combination, with a support and means for securing the same in operative position, of a shaft on the support, a rotary head on the shaft, provided with revoluble upsetting-wheels to engage and travel upon the tube end, a confined spring upon the shaft, bearing against the rotary head to press the upsetting-wheels against the tube end, tensioning means upon the shaft for the said spring, and means for turning the said head, substantially as described.

2. In a device for upsetting and beading the ends of tubes, the combination, with means for securing the device in operative position, of a series of rotary upsetting and beading wheels mounted in revoluble bearings to engage and travel upon the tube end, one or more wheels of the series being provided with a cutting-edge h' to shave off the edge of the tube during the beading operation, and means for pressing the upsetting and beading wheels against the tube end and for revolving the bearings, substantially as and for the purpose set forth.

3. In a device for upsetting the ends of tubes, means for securing the device in operative position, comprising, in combination, an expandable sleeve adapted to enter a tube provided with an annular shoulder s^5 on its outer circumference and a conical opening, and a conical expansion-core to enter said opening and expand the sleeve against the inner circumference of the tube and cause the shoulder s^5 to form a circumferential bead t on the tube and engage the groove under the said bead, substantially as and for the purpose set forth.

4. In a device for upsetting the ends of

tubes, the combination, with a support and means for securing it in a tube, of a frame adjustably mounted between its ends upon the support, a set-screw upon one end portion 5 of the frame, having a base to engage a tube end, upsetting mechanism on the opposite end portion of the frame, and means upon the

support for clamping the upsetting mechanism against a tube end, substantially as described.

JOHN D. MURPHY.

In presence of—

M. J. FROST,

W. N. WILLIAMS.
